UNITED STATES PATENT OFFICE.

WILLIAM H. H. WELTON, OF DENVER, COLORADO.

METAL TIE AND RAIL-FASTENER.

1,388,226.

Specification of Letters Patent. Patented Aug. 23, 1921.

Application filed July 29, 1920. Serial No. 399,940.

To all whom it may concern:

Be it known that I, WILLIAM H. H. WELTON, a citizen of the United States, residing at the city and county of Denver and State 5 of Colorado, have invented certain new and useful Improvements in Metal Ties and Rail-Fasteners; and I do declare the following to be a full, clear, and exact description of the invention, such as will enable 10 others skilled in the art to which it appertains to make and use the same, reference being had to the accompanying drawings, and to the characters of reference marked thereon, which form a part of this specification. 15

The object of this invention is to provide a tie and fastener for rails which can be quickly adjusted and quickly laid, and having no parts which will readily loosen when 20 in use.

Briefly, the invention comprises a tie of trough or channel shape, adapted to receive a pair of fasteners slideable longitudinally of the tie and having means to engage opposite 25 sides of the rail. Wedge shaped devices are provided for anchoring the fasteners within the tie, thereby preventing movement of the rail upon the tie.

In the drawings:

30 Figure 1 is a plan showing the parts in operative relation, the rail being removed.

Fig. 2 is a view taken from line 2—2 of Fig. 1, but showing a rail in position.

Fig. 3 is a similar view, showing the invention applied at a joint opposite a block signal tower, where the rails are required to be insulated.

40 Fig. 4 is an enlarged view of one of the fasteners before being bent into operative shape.

Fig. 5 is a partial longitudinal section through a tie, showing the construction of Fig. 3, one of the fasteners being omitted.

Fig. 6 is a longitudinal section showing 45 one of the fasteners provided with a modified form of rail-engaging means.

Fig. 7 is a perspective view of the tie alone.

Fig. 8 is a perspective of a plate used 50 when insulation is required.

Figs. 9 and 10 are perspectives of two forms of bridges adapted to be used within the tie and beneath the rail.

Fig. 11 is a perspective of the form of fastener shown in Figs. 3 and 5.

Fig. 12 is a perspective of the fastener used at the right of Fig. 6.

Each tie 15 has shallow recesses 16 cut in the top of each side thereof and adjacent each end, said recesses being of a width 60 equal to the width of the rail bases and adapted to receive the bases.

Two fasteners 18 and 20 are provided for each rail, these fasteners ordinarily being identical in construction and adapted when 65 in operative position to be slid longitudinally within the tie and to produce a snug fit. Each fastener comprises a plate portion 21 and a longitudinally extending arm 22 at each side thereof. A bracing tongue 70 23 extends from the plate 21, this tongue lying between and being severed from the arms 22. The arms 22, as seen in Fig. 4, are bent upward to U-shape, so as to be mounted longitudinally within the tie, as shown. The 75 tongue 23 is bent to engage the base of the rail. Each arm 22 is provided with a long slot 24 and a shorter slot 25, a slot 24 in one arm being opposite a slot 25 in the opposite arm, these slots being adapted to receive 80 tapered locking keys 26 which also pass through long slots 27 and short slots 28 in the tie 15, a short slot being placed opposite each long slot in the tie as in the fasteners. In positioning the fasteners 18 and 20, one 85 arm of one fastener is positioned inside of the adjacent arm of the other fastener, while the opposite arms are reversely disposed.

Referring to Fig. 1, the arms of the fastener 18 are indicated by numerals 122 to 90 distinguish from the arms 22 of fastener 20, one arm 22 of fastener 20 being positioned inside of the adjacent arm 122 while the opposite arm 22 is positioned outside of the opposite arm 122. This permits the fasteners to be identical in construction.

In order to provide a suitable support for each rail, bridges are provided which are adapted to be positioned between the arms of the fasteners and between the tapered 100 keys 26. One form of bridge is indicated at 30 in Fig. 10, this bridge being of inverted U-shape, and having a supporting face 32. Another form of bridge is shown at 31 in Fig. 9, this form being closed but having the 105 supporting face 32 as in Fig. 10.

In order to provide means for bracing the rails on curves, the tongue 23 may have an extension 123, as indicated in Figs. 6 and 12, the upper end of said extension engaging 110

the web of the rail R. Where the fastener is to be used at joints, the tongue 23 may have an extension 223 positioned to lie flat against the web of the rail 5 and provided with holes 35 to receive bolts 36, whereby fish plates may be dispensed with, at least on one side of the rail. The same style of brace may be used on the opposite side if desired, or a fish plate may be 10 used.

Where block signals are employed and the rails are required to be insulated opposite the towers, insulation 40 is placed between the ends of the rails, and insulation 41 in 15 sheet form and of a length substantially equal to the width of the tie, is folded around the base and web of the rail before installation, this construction being shown in use in conjunction with the tongue extension 223 20 and fish plate 42. An insulating sleeve 43 is also employed for each bolt 36.

In order to avoid cutting of the insulation 41, a spanning plate 45 is provided, whose length is equal to the width of the 25 tie, this plate having upstanding sides 46 to lie along the edges of the rail base and having depending flanges 47 at its ends to overhang the sides of the tie and provide a smooth continuous bed for said insulation.

From the foregoing, it will be seen that I have provided simple and efficient means for supporting and anchoring rails and for insulating the same where required. The 35 tapered keys 26 when driven through the various slots of gradually decreasing lengths are firmly anchored and may be securely retained by bending down the small end along the side of the tie with a hammer. 40 Thus, there is nothing which can work loose and the ties will be secured to the rail permanently, renewal being required only when the ties have completely rusted out.

45 It should be noted that the bridge 30 may be made so as to extend either longitudinally or transversely of the tie.

I claim:

50 1. In combination a trough shaped tie, a pair of members slidable within the tie, said members being of a width equal to the width of the inside of the tie minus the thickness of the material, each member being provided with two parallel sides one 55 end of which is joined by a web and provided with tongues for engagement with the flanges of a railroad rail and means for securing said members to the tie and clamping them against the flange of the rail.

60 2. In combination a trough shaped tie, a pair of members slidable within the tie, said members being of a width equal to the width of the inside of the tie minus the thickness of the material, each member being 65 provided with two parallel sides, one end

of which is joined by a web and provided with tongues for engagement with the flanges of a railroad rail, the sides of said members being each provided with two slots of unequal length, said slots being reversely arranged, coöperating slots in the sides of the tie and means coöperating with said slots for securing said members to said ties and clamping the tongues against the flanges of a railroad rail.

70 3. In combination a trough shaped tie, a pair of members slidable within the tie, said members being of a width equal to the width of the inside of the tie minus the thickness of the material, each member being provided with two parallel sides, one end of which is joined by a web and provided with tongues for engagement with the flanges of a railroad rail, the sides of 75 said members being each provided with two slots of unequal length, said slots being reversely arranged, coöperating slots in the sides of the tie, means coöperating with said slots for securing said members to said ties and clamping the tongues against the flanges of a railroad rail, an extension on one of 80 said tongues for engagement with the web of a railroad rail.

85 4. In combination a trough shaped tie, a pair of members slidable within the tie, 90 said members being of a width equal to the width of the inside of the tie minus the thickness of the material, each member being provided with two parallel sides, one end of which is joined by a web and provided with tongues for engagement with the flanges of a railroad rail, the sides of 95 said members being each provided with two slots of unequal length, said slots being reversely arranged, coöperating slots in the sides of the tie, means coöperating with said slots for securing said members to said ties and clamping the tongues against the flanges of a railroad rail, an extension on one of said tongues for engagement with the web of a railroad rail.

100 5. In combination a trough shaped tie, a notch in the upper edges of the sides of the tie near each end thereof, railroad rails, seated in said notches, a pair of members slidable within said tie, near each end thereof, said members being of a width equal to the width of the inside of the tie minus the 105 thickness of the material of which they are made, each member comprising two parallel sides one end of which is joined by a web, said members being each provided with a tongue for engaging the flanges of the 110 railroad rail, a spanning plate between the bottom of the rail and the top of the tie, means for insulating the rail from said spanning plate and from said tongues and 115 means for securing said members to said 120 railroad rail.

125 6. In combination a trough shaped tie, a pair of members slidable within the tie, said members being of a width equal to the width of the inside of the tie minus the thickness of the material, each member being 130 provided with two parallel sides, one end

tie and forcing said tongues against said flanges.

6. In combination a trough shaped tie, a notch in the upper edges of the sides of the tie near each end thereof, railroad rails, seated in said notches, a pair of members 5 slidable within said tie, near each end thereof, said members being of a width equal to the width of the inside of the tie minus the thickness of the material of which they 10 are made, each member comprising two parallel sides one end of which is joined by a web, said members being each provided with

a tongue for engaging the flanges of the railroad rail, a spanning plate between the 15 bottom of the rail and the top of the tie, a bridge member between the bottom of the tie and the bottom of said spanning plate, means for insulating the rail from said spanning plate and from said tongues and 20 means for securing said members to said tie and forcing said tongues against said flanges.

In testimony whereof I affix my signature.

WILLIAM H. H. WELTON.
